(57) **CLAIM**

The ornamental design for a filter arrangement, as shown and described.

DESCRIPTION

FIG. 1 is a perspective view of a filter arrangement showing my design,

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The broken lines shown in the figures are for the purpose of illustrating portions of the filter arrangement and form no part of the claimed design.
